WEED BURNER

Filed April 29, 1937

UNITED STATES PATENT OFFICE

2,144,491

WEED BURNER

George J. Heberlein, Greeley, Colo.

Application April 29, 1937, Serial No. 139,751

6 Claims. (Cl. 126—271.2)

My invention relates to portable gasolene torches, or what are known as cactus burners or weed burners.

In some farming districts grasshoppers become a plague. When the spring crops are planted in the ground, there is little vegetation in the fields except along the ditches and fences.

If, at the proper times, the farmer goes along the ditches and fences operating a good gasolene torch, he will not only burn the weeds, but what is much more important, he will singe and kill all the grasshoppers that fly up into the flame of the torch. So, my torch might also be called a grasshopper burner.

Many such burners have been invented. The following are good examples of the prior art:—Beever, No. 630,823; Allison, No. 634,130; Snowden, No. 638,650; Snowden, No. 657,036; Myers, No. 742,344; Farley, No. 872,920; Ploch, No. 1,058,900; Taylor, No. 1,231,969; Monroe, No. 1,295,349; and Blackwell, No. 1,625,702.

But, none of them are perfectly satisfactory.

A good weed burner should be able to stand the rough usage to be expected on a farm, without being too heavy to be carried easily. None of these prior art burners are constructed to stand rough usage.

The generator coils must be made of copper or brass tube; in order to be bent into a coil without breaking or splitting this tube must be quite soft and easy to bend. None of these above mentioned patents supports the generator coils on the feed pipe handle except by the soft weak coil tube alone. Any rough usage, or a fall by the operator and the generator coil is bent out of place and must be repaired before the work can continue. With a wind at his back the operator often proceeds at a slow run, so the ability of the burner to stand rough usage is of very great importance. None of these prior art structures clamp the housing on the handle and clamp the generator coils to the housing for support.

A good weed burner should operate perfectly on a cold day or on a windy day, which means a good burner should have a proper housing. All of these above mentioned weed burners have either no housing at all, or a housing wide open at both ends, or a housing not extending all about the generator, or a housing spaced too far from the generator or a housing not extending far enough forward in front of the generator, so that from one cause or another the generator will not be hot enough for proper generation on a cold day, or on a windy day a strong wind will either cool

off the generator till it will not generate, or the wind may even blow the flame out.

So, on a windy day or a very cold day, these above cited burners will not give perfect satisfaction, and may even refuse to give service at all. 5

All of these prior art structures have just one flame, which is substantially circular in section; none of them provide a wide flame that will cover more ground area than a single flame will cover. And none of them provide a cover which would 10 properly cover and shield from the wind two or more generators, if such were provided.

The housings shown are round or circular and are attached to the generator coils, but none of them are supported by being clamped to the handle of the burner. All these burners show the generator coil to be unsupported as far as the clamping of the housing on the handle is concerned, and this makes an inherently weak point in the construction of them all. None of them 15 show a feed pipe for a handle with a T at the end of the feed pipe for properly clamping the housing to the feed pipe.

The object of my invention, therefore, is to provide a burner in which the housing is firmly 25 clamped to the feed pipe handle to form a strong extension thereof, and to which housing the generator means is clamped, to form a strong, stiff unit that no ordinary rough usage can in any way damage. 30

A further object is to provide a burner that will operate perfectly on cold or windy days by providing a housing that is open at the front end only and in which the front of the housing extends far beyond the front ends of the generator 35 coils, the housing clearing the sides of the coils enough for proper ventilation and combustion, but not enough to permit the wind to blow in and upset the proper operation of the burner; air for proper combustion being let into the housing by a 40 slight opening about the centrally located handle, and by an air hole through the housing for each generator coil.

A further object is to provide multiple generators whose axes are in the same plane, but are 45 divergent, and which combine to throw a broad flame and cover much more ground area than any single flame generator can cover. The heat from each generator and flame is thus added to by the heat from one or more of the other flames, and 50 this feature combines with the closed housing to insure perfect generation under all weather conditions.

A further object is to provide a flattened or oblong cover or housing instead of the usual 55

round housing so that the oblong housing will properly cover the multiple generators so as to protect them from the wind and retain within the housing enough heat for proper generation at 5 all the generators.

A further object is to provide clamping means to clamp this oblong cover or housing to a T-shaped feed pipe handle, so there will be no movement between them.

10 A further object is to provide a combination of housing and multiple generator coils and T-shaped feed pipe handle, that will rigidly support the coils on the handle by means of the housing, will prevent wind from cooling the generators or blowing out the flames, and that will nevertheless provide ample air for perfect combustion at all the generators.

I attain the above mentioned objects by attaching two or more generators with their coils 20 in the same plane, to a common handle or fuel line, that is T-shaped at its end, positioning the generators so their flames, though in the same plane, are slightly divergent, so as to cover as broad a path as possible, and then clamping the 25 T-shaped feed handle and the coils to a reinforced sheet-metal housing enclosing the coils and the front end of the handle, and closed except at the front, and except for openings for the proper amount of air to support perfect combustion at all the generators.

The details of this construction will be more fully explained with reference to the drawing, in which—

Figure 1 is a general view of the burner, shut-off fuel valve, feed pipe handle, hose connection, fuel tank, air pump in the top of the tank, and shoulder strap for carrying the fuel tank. The fuel tank and connection to the feed pipe handle are not parts of my invention, but are shown as 40 they operate with my weed burner.

Figure 2 shows a sectional view of the housing or cover, looking down on the generators, feed handle and shut-off valve.

Figure 3 shows a side elevation of a portion of 45 the feed handle and generator coil assembly clamped to the housing, with the housing shown in section.

Figure 4 shows an elevation of my weed burner as seen from the front, and with a portion of 50 the housing shown in section.

Figure 5 shows a view of the T end of the tubular feed handle and portions of four generator coils.

Figure 6 is a fragmentary detail showing the 55 formation of the crimp for crimping the parts of the housing together.

The tubular feed handle 1, may be of ordinary threaded iron pipe, which is properly connected to the hose 2, and the hose 2 is properly connected to the fuel tank 3, whose air pump 4 is employed to put air pressure upon the gasoline or other fuel in the tank 3, so as to force it to the burner.

60 The tubular feed handle 1, may be composed of any other strong and proper tubular material that will not only carry the fuel, but that will be strong enough to stand rough usage.

The shut-off valve 5 is threadedly connected 70 to the handle 1 and to the shut-off valve 5 is threadedly attached the front member 6, of the handle.

The member 6 of the handle is composed of a short piece of pipe provided with threads at each 75 end to engage the shut-off valve 5 and the T 7

respectively. The nipples 8, 8, are screwed into the T 7.

To the nipples 8, 8, are screwed the street L's 10, 10; and to the street L's 10, 10, are screwed the fittings 11, 11.

5 To the fittings 11, 11, are screwed the fittings 12, 12.

The coils 13, 13, are provided with the unions 14, 14, and are attached thereby to the fittings 12, 12. The course of the fuel is from the tank 10 3, and in turn through the hose 2, the handle 1, shut-off valve 5, the front end 6 of the handle, the T 7, the nipples 8, 8, the street L's 10, 10, the fittings 11, 11, and 12, 12, the unions 14, 14, the coils 13, 13, and out of the apertures 19, 19, of 15 the caps 18, 18.

The fuel passes from the unions 14, 14, through the coils 13, 13, to the apertures 19, 19, in the caps 18, 18, which apertures are so located at the rear ends of the coils 13, 13, as to spray the fuel 20 forward through the coils, the apertures 19, 19, being substantially aligned with the axes of the coils.

On the forwardly pointing front end of this rear end of the coil is the fitting 15, the fitting 16, 25 the screen 17 and the cap 18, which cap 18 is provided with a small hole 19 through which the fuel feeds in the form of a gas, when the generator is hot.

As the gasoline or other proper fuel is fed to 30 the generators from the T-shaped feed handle, it first passes to the front end of the coil and then back and around and around through the coil and finally passes out the hole 19. By the time the fuel reaches the hole 19, it is in the 35 form of fuel vapor. This fuel vapor is sprayed forward to the coil and through the coil 13, and by this movement it is mixed with air necessary to support combustion and is thrown forward out of the burner as a great flame. The feed handle 1, valve 5, member 6, T 7, nipples 8, L's 10, fittings 11 and 12, coils 13, unions 14, fittings 15 and 16, screen 17 and cap 18, all combine to form 40 what may be called the feed handle unit.

In Figures 2 and 4 it will be seen that the coils 13, 13 are not parallel, but though they are in the same plane, which is parallel to the T-shaped handle, their outer ends spread slightly so as to make the flames cover as wide a path as possible 45 leaving substantially no interval between the 50 two flames.

The housing is composed of the flat top 20, the bent bottom 21, and the two bent sides 22.

These four pieces of the housing or cover are attached together by means of the form of crimp 55 shown in Figure 4.

The two sides have their upper and lower edges bent to form an angle as at 23.

The edges of the top 20 and of the bottom 21 are crimped to form recesses as shown in Figure 60 6 and to receive the angles 23 of the sides 22. At this stage the flaps 24 are horizontal, leaving the recesses open to receive the angles 23. These parts are first assembled as shown in Figure 6 and the flaps 24 are then crimped down in place 65 as shown in Figure 4, thus locking all the parts together.

When the four parts of this housing are thus assembled, the crimps along the four corners of the housing act to reinforce the housing and to 70 stiffen it to a surprising degree, without increasing the weight to any appreciable extent.

It will be seen as indicated at 25 in Figures 2 and 3, that the housing clears the front tubular member 6 enough to let in some air for combus- 75

tion, but not enough air to chill the generators or to blow out the flames. When looking down on the burner it will be seen that this air passage around the tubular member 6 is centrally located, so that the air from about the feed handle will not only act to cool the feed handle, but will pass quite equally to all the generators.

The holes 26, 26, directly to the rear of each generator coil 13, supply more air for combustion and this air coming in from the side of the air entering from about the handle and mixing with it tends to produce turbulence and better mixing of the air with the vapor from the spray holes 19, 19.

15 The clamp 27 fits about the front end 6 of the feed handle and the screw 28 and nut 29 and washer 30 act to firmly clamp the T-shaped feed handle to the top 20 of the housing.

Because the T-piece 1 and the street L's 10, 10, 20 are thicker than the front end 6 of the feed handle, this clamp 27 puts the top 20 of the housing under quite a bending strain which tends to all the more firmly clamp the T-shaped handle and the housing together.

25 The clamps 31, screws 32, nuts 33, washers 34, and spacers 34' are employed to firmly clamp the outer ends of the coils 13, 13 to the bottom 21 of the housing but slightly spaced therefrom, thus forming a three point clamp for the handle and 30 the coils to the housing.

The result is a most surprising strong, stiff and light unit, with the weak or springy coils well protected and supported and held solidly in place.

35 In Figure 5 is shown the T-shaped handle as it would appear for a four generator torch.

In place of the two street L's 10, 10, as shown in Figures 2, 3, and 4, the two T's 36, 36, are screwed to the nipples 8, 8; the coils 13, 13, are then attached to the T's 36, 36. Then the nipples 8', 8', are attached to the T's 36, 36, then two more T's 36, 36, are attached to the nipples 8', 8'. Then the two coils 13, 13, are attached to these last T's 36, 36, and the plugs 35, 35, are 45 screwed into the ends of these last T's 36, 36.

If still more than four generators are desired, the plugs 35 are replaced by nipples 8' and T's 36 as more generators are added, the plugs 35 being put in the ends of the outer T's, or the 50 outer T's and plugs may be replaced by street L's such as shown in Figures 2, 3, and 4.

The housing in a four or more generator torch will be of the same general construction as that described above, but the top and bottom pieces 55 will be made wide enough to accommodate the additional generators. The T-shaped handle will be clamped to the top of the housing in the same way, or perhaps with more than one clamp 27; and the front end of each generator coil 13, will 60 also be clamped to the bottom of the housing in the same way; and there will be an air hole 26 back of each generator coil, through the top or bottom of the housing, and of course the housing 65 will fit the handle freely for the admission of more air for combustion and which air acts to cool the handle.

The axes of the generator coils are made divergent enough to cause their flames to cover as 70 much ground surface as possible without leaving too much space between adjoining flames, as shown in Figure 5.

In this way the flames from burners having more than two generator coils will be just as hot 75 and will work just as perfectly regardless of wind-

or cold, as those burners having only two generator coils.

If for any reason the screens 17 or the spray nozzles 19 become stopped up with dirt of any kind, the burner may be easily taken apart as 5 follows:—

Remove the clamping screws 32, nuts 33, washers 34 and spacers 34'.

Unscrew the front end 6 of the handle from the shut-off valve 5; remove the screw 28, washer 10 30 and nut 29, and then pull the front end 6 of the handle and the coils 13, 13 forward and out of the housing. After cleaning the parts should be reassembled by reversing the proceeding. If clean fuel is used, however, there will be little 15 need for taking the burner apart.

Having now described my invention, what I claim as new, and desire to protect by Letters Patent, is as follows:—

1. In a weed burner, a rigid tubular, T-shaped fuel feed handle, a plurality of flexible tubular generating coils, each attached at one end to the T-shaped feed handle, a single reinforced sheet metal housing open at the front end and enclosing the T-shaped end of the feed handle and 20 all of the coils and slightly spaced from the handle, the housing being slightly spaced from the coils, clamping means including a metal member clamped about the handle securely attaching the housing to the handle, and clamping means including a metal member clamped about each coiled tube, securely attaching each coil to the housing to support the coils upon the housing and provide a light but strong and rigid burner unit. 35

2. In a weed burner, a T-shaped fuel feed handle having a tubular central portion and a T portion extending on opposite sides thereof, two tubular generating coils attached to the fuel feed handle out of line with the central tubular portion, one end of each coil being connected to the T portion of the feed handle and the other end of each coil being provided with a fuel spraying orifice adapted to spray fuel forward through the coil, a housing open at the front end and 40 enclosing the coils and the T end portion of the feed handle, clamping means including a member clamped about the feed handle, securely attaching the housing to the handle, and clamping means including a member clamped about the tube of each of said coils, securely attaching each coil to the housing. 45

3. In a weed burner, a rigid tubular feed handle to be connected to a fuel supply and having a fuel shut-off valve, a plurality of separate flexible generating coils connected to the handle and each having a spray nozzle co-axial with and to the rear of the coil to spray fuel forward through the coil, said feed handle and said coils forming a feed handle and coil unit, a 55 separate housing enclosing the said coils and surrounding and slightly spaced at one end from the forward portion of the feed handle to permit the inlet of air to cool the handle and to support the combustion of the fuel sprayed from 60 said nozzles and open at the opposite end, and removable means attaching the housing securely to the said feed handle and coil unit, whereby removal of said means will permit the housing to slide longitudinally from about said coils. 65

4. In a weed burner, a tubular feed handle to be connected to a fuel supply and having a shut-off valve and having its front end in the form of a T, a plurality of generating coils in a row, which row is slightly to one side of and parallel 70 75

- to the T of the feed handle, each generating coil connected at one end to the T of the handle and each coil having a spray nozzle at its other end to the rear of and co-axial with the coil to spray gasified fuel forward through the coil, said feed handle, said T and said coils forming a feed handle and coil unit, a housing enclosing the coils and whose inner surface is slightly spaced therefrom and surrounding the forward portion of the handle and slightly spaced therefrom to provide an air inlet whereby the air coming into the housing for supporting the combustion of the gasified fuel will tend to cool the handle, and supporting means supporting the housing on said feed handle and coil unit, whereby removal of said supporting means will permit the housing to slide backward from about the coils.
5. In a weed burner, a rigid feed handle, two flexible coils, each connected at one end to the feed handle, and a single rigid housing fitting about but slightly spaced from the coils, the inner surface of the housing being slightly spaced
- 10
- 15
- 20

from the feed handle, and means including a band of metal clamping about the feed handle to attach the housing to the feed handle, and means including bands of metal clamping about each coiled tube adjacent its front end, to attach the coils to the housing, whereby the flexible coils are securely mounted on the rigid feed handle through the housing.

6. In a weed burner having a rigid fuel feed handle and flexible generator means of tubing attached to the handle, a housing open at its front end and surrounding the end of the feed handle and longitudinally movable thereon and slightly spaced therefrom at its rear end to permit the entrance of cooling air along the feed handle, and enclosing the said generator means but slightly spaced therefrom to conserve the heat, said handle and generator means forming a feed handle and generator means unit, and means attaching the housing securely to said feed handle and generator means unit.

GEORGE J. HEBERLEIN.
